UNITED STATES PATENT OFFICE.

ISAAC G. PERRY AND FRANK F. FULCHER, OF GREAT BARRINGTON, MASSACHUSETTS.

DESIGN FOR A HANDLE FOR SPOONS, FORKS, OR SIMILAR ARTICLES.

No. 39,398.

Specification for Design.

Patented July 7, 1908.

Application filed April 27, 1908. Serial No. 429,578. Term of patent 7 years.

To all whom it may concern:

Be it known that we, ISAAC G. PERRY and FRANK F. FULCHER, both citizens of the United States, also both residing at Great Barrington, in the county of Berkshire and State of Massachusetts, have invented a new, original, and ornamental Design for a Handle for Spoons, Forks, and other Similar Articles, of which the following is a specification, reference being had to the accompanying drawing, forming part thereof.

The figure is a plan or front view for a handle for spoons, forks or similar articles, showing our new design.

We claim:

The ornamental design for a handle for a spoon, fork, or similar article, as shown.

ISAAC G. PERRY.
FRANK F. FULCHER.
